UNITED STATES PATENT OFFICE.

ROY E. GUNSOLUS, OF SAN JOSE, CALIFORNIA.

CHALKING DEVICE FOR BILLIARD-CUES.

No. 868,549.

Specification of Letters Patent.

Patented Oct. 15, 1907.

Application filed April 25, 1907. Serial No. 370,325.

To all whom it may concern:

Be it known that I, ROY E. GUNSOLUS, a citizen of the United States, and a resident of San Jose, in the county of Santa Clara and State of California, have made a certain new and useful Invention in Chalking Devices for Billiard-Cues; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a perspective view of the invention. Fig. 2 is a central longitudinal section of the same. Fig. 3 is a similar view showing the chalk and holder separately. Fig. 4 is a similar view illustrating the use of the limitation device for the chalk.

The invention has relation to holders for billiard chalk, and it consists in the novel construction and combinations of parts as hereinafter set forth.

The object of the invention is to provide a holder from which the chalk cannot be removed until it is worn out or broken; to save chalk, and time in serving the same; to facilitate proper application of the chalk to end of cue, and to keep the chalk free from dust without interfering with its ready application.

In the accompanying drawings illustrating the invention the letter *a*, designates the holder; *b*, a piece of chalk therein; *c*, a piece of paper or fabric surrounding the chalk, and *d*, a suspension cord.

The holder *a*, consists of a cylindrical body, having a cylindrical cavity extending upward therein, the bottom being open and having a rounded margin, as shown. The cavity is made deeper than the length of the chalk block, so that when the latter is in place in its seat there will be a chamber *e*, above it in the cavity, said chamber being continuous with the seat portion and of the same diameter. The side walls of the holder body, which is usually made of wood are designed to 35 clasp the chalk by their inherent elasticity, and in order that this may be more effectively accomplished they are made rather thin of the same thickness throughout and the holder and the cavity therein of considerably greater length than the chalk cylinder. Inasmuch as 40 the elasticity of the side walls of the holder is of limited character, when the chalk cylinder is forced into its seat, so that its outer end lies slightly within the outer end of the seat, it is difficult to force it farther into the seat. In practice an effectual stop is thus provided

against further movement of the chalk within the seat. 50 The holder and its seat for the chalk is made cylindrical in form to obtain an even expansion of the thin side walls and to avoid splitting such walls. Through the center of the top is made an aperture *f*, through which the suspension cord is passed, its lower end being 55 knotted as at *g*, such knotted portion being secured and held in a tapered enlargement *f'*, of such aperture which prevents the knot from becoming loose or cut by sharp corners and keeps it out of the way.

The device being suspended by attachment of the 60 upper end of the cord to a screw eye in the ceiling or otherwise, is always in position for use, and the chalk being covered in by the holder above and at its sides is protected from dust. The holder is of sufficient length to suit the fingers in applying the chalk, and the round- 65 ed edge of the opening of its cavity serves to prevent injury to the cue tip.

When the chalk is worn out the shell thereof may be broken and knocked into the inner clearance chamber from whence the pieces thereof will drop out. 70

In order to properly adjust the chalk in position and prevent it from being placed too deeply in the holder, as well as to maintain the clearance chamber *e*, a limitation device, such as a transverse pin *h*, extending across the cavity at the top of the chalk seat portion, 75 may be employed, although this is not considered essential.

Having thus described my invention, what I claim and desire to secure by Letters Patent is—

1. A chalk holder for use in playing billiards consisting 80 of a cylindri-form body having a central cylindrical cavity of the same dimensions throughout and consisting of an outer chalk seat portion and an inner clearance chamber, the side walls of such body being of thin elastic character having the same thickness throughout.

2. A chalk holder for use in playing billiards consisting 85 of a cylindri-form body having a central cylindrical cavity, of the same dimensions throughout and consisting of an outer chalk seat portion and an inner clearance chamber, the side walls of such holder being of thin elastic character having the same thickness throughout, said body having an end wall provided with a central perforation having a tapered enlargement at its inner end leading into such clearance chamber, and an attachment cord extending through such perforation and having a knot and 90 its stop end located within such tapered enlargement.

In testimony whereof I affix my signature, in presence of two witnesses.

ROY E. GUNSOLUS.
